Herbert G. Odum
HIS ATTORNEY

UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

AIR-FEED LOCK FOR ROCK DRILLS.

Application filed May 5, 1922. Serial No. 558,778.

To all whom it may concern:

Be it known that I, FRED M. SLATER, a citizen of the United States, and a resident of Easton, county of Northampton, and

5 State of Pennsylvania, have invented a certain Air-Feed Lock for Rock Drills, of which the following is a specification, accompanied by drawings.

This invention relates to fluid actuated 10 rock drills but more particularly to a device for controlling the feeding element of a stope drill, although the invention may be applied to any drill having a fluid actuated feeding element.

15 The objects of the invention are to enable the members of the fluid actuated feeding element of a stope drill for instance, to be positively locked against relative movement when desired, and effect the control of the 20 locking devices preferably by fluid actuated means under the manual control of the operator.

To these and other ends which will hereinafter appear, the invention consists of the 25 combinations of elements and arrangement of parts substantially as described and claimed in this specification, and shown in one of its preferred forms in the accompanying drawings, in which—

30 Figure 1 is a side elevation in longitudinal section of so much of a stope drill as will serve to illustrate the invention,

Figure 2 is an enlarged detail vertical sectional elevation of the feeding element,

35 Figure 3 is an enlarged detail sectional elevation partly broken away of the lower portion of the feeding element on the line 3—3 of Figure 2, looking in the direction of the arrows, and

40 Figure 4 is a sectional view of Figure 2 on the line 4—4 looking in the direction of the arrows.

Referring to the drawings, the cylinder A is provided with the reciprocating piston B and the drill steel C extends within the front head D in position to receive the impact blows of the piston delivered upon the anvil block E. Since the distribution of motive fluid to the cylinder forms no part 50 of the present invention, the ports and passages are not indicated.

The cylinder is provided with a head block F containing the throttle valve G having the handle H controlling the supply of 55 motive fluid from the inlet J to the cylinder

and to the air feeding element. The rotation handle K provided with a valve for controlling the feeding element, is also connected to the head block F.

A head block extension L is located between the head block F and the feed cylinder O, adjacent the feed cylinder flange P. The parts so far described are adapted to be secured together by the usual side bolts (not shown).

In the form of fluid actuated feeding element illustrated, the feed cylinder O, forming one of the two relatively movable members, is connected to the cylinder A and its associated parts while the piston Q and 70 piston rod R forming the other feeding element member, are stationary and provided with the rock engaging pointer S.

Means are provided for positively locking the feeding element members against 75 relative movement, and for this purpose, inter-locking devices are provided on said elements, which may take the form of a rack T on one of said members, cooperating with means carried by the other member for positively engaging and inter-locking with the rack and thereby positively locking the members against relative movement.

In the present instance, and as a convenient construction, the rack T is suitably 85 secured within the piston rod R as by means of the screws U and a toothed member or members may be carried in a gear support or housing V connected by the gear housing support W to the head block extension L so 90 that the toothed member or members of the gear support or housing move with the feed cylinder O.

A suitable and convenient form of locking device is that shown in the drawings, and 95 consists of a gear X rotatable on the spindle Y carried in the housing V and meshing with the rack T. Another gear a is rotatable on the spindle b carried in a yoke c slidable in the housing V and normally separated from the gear X by the coil springs d as indicated in Figure 1 and as shown in detail in Figure 3, but said gear a is in constant engagement with the rack T, and with the parts in such position, the members of 100 the feeding element are free to move relatively for feeding the machine.

In order to lock the feeding mechanism from movement, means are provided for causing the gear a to engage the gear X as 110

indicated in Figures 2 and 3, and for this purpose, fluid actuated means under the control of the operator are preferably provided. A rod *e* extends through the gear housing support *W* and bears at its lower end upon the yoke *c*. A spring *f* normally retracts the rod *e* and at its upper end, the rod cooperates with a piston *g* in a chamber in the head block extension *L* to which chamber fluid pressure from the supply may be admitted by manipulating the manually controlled valve *h* mounted on the rotation handle *K*.

From the inlet *J* a passage *j* leads to the bore of the hollow handle *K* and a differential valve *k* having the heads *o* and *p*, is movable in said handle. A port *q* leads from the handle to the piston *g*, and the hollow bore of the handle *K* is open to atmosphere at one end *r* so that when the hand controlled valve *h* is in open position, as indicated in Figure 1, the bore of the handle is also vented to atmosphere at the opposite end through the port *s* located in a sleeve *s'*. Under these circumstances, pressure supplied to the valve *k* between the heads *o* and *p* will force the valve to the right, as indicated in Figure 1, since the pressure area of the head *p* is greater than the area of the head *o*. When the port *s* in the handle is closed by the valve *h*, the leakage of fluid pressure from the supply around the head *p* of the valve *k*, will build up pressure on the face *t* of the said head *p* and as the opposite end of the valve is open to atmosphere through the end *r* of the rotation handle *K*, the valve will be moved to the left a sufficient distance to connect the passage *j* with the port *q* and supply pressure above the piston *g* which forces the piston downwardly and presses the yoke *c* downwardly to carry the gear *a* into the engagement with the gear *X*. The gears will then be interlocked and as they both engage the rack *T* relative movement between the members of the feeding element is prevented, and said members are positively locked.

I claim:

1. In a fluid actuated rock drill, the combination of a cylinder, a fluid actuated feeding element having relatively movable members, one being connected to said cylinder, and the other being stationary, and inter-engaging means for preventing movement of the feeding element members, comprising three members, two of said members being in constant engagement with the third member, and means for positively locking said three members together.
2. In a fluid actuated rock drill, the combination of a cylinder, a fluid actuated feeding element having relatively movable mem-

bers, one being connected to said cylinder, and the other being stationary, and fluid actuated means for positively locking said feeding element members against relative movement, said means including a pair of relatively movable toothed members.

3. In a fluid actuated rock drill, the combination of a cylinder, a fluid actuated feeding element having relatively movable members, one being connected to said cylinder, and the other being stationary, and fluid actuated interlocking devices for positively locking said feeding element members against relative movement, said devices including a rack and gear, said gear being adapted to be moved on the rack independently of the movement of the feeding element.

4. In a fluid actuated rock drill, the combination of a cylinder, a fluid actuated feeding element having relatively movable members, one being connected to said cylinder, and the other being stationary, a rack on one of said members, and fluid actuated means carried by the other member and movable along the rack for positively engaging and interlocking with the rack for positively locking said members against relative movement.

5. In a fluid actuated rock drill, the combination of a cylinder, a fluid actuated feeding element having relatively movable members, one being connected to said cylinder, and the other being stationary, a rack on one of said members, a gear carried by the other member engaging said rack, and fluid actuated means adapted to engage said rack and gear for locking said gear against rotation.

6. In a fluid actuated rock drill, the combination of a cylinder, a fluid actuated feeding element having relatively movable members, one being connected to said cylinder, and the other being stationary, a rack on one of said members, gears carried by the other member engaging said rack, and fluid actuated means for interlocking said gears.

7. In a fluid actuated rock drill, the combination of a cylinder, a fluid actuated feeding element having relatively movable members, one being connected to said cylinder and the other being stationary, and interengaging means for locking the feeding element members against movement, comprising three toothed members, two of said members being carried by one of the feeding element members, and fluid actuated means for locking the three members together.

In testimony whereof I have signed this specification.

FRED M. SLATER.
